PAINT SPRAY GUN

Albert Di Stefano, Philadelphia, Pa.

Application August 25, 1948, Serial No. 46,079

14 Claims. (Cl. 299—122)

1

This invention relates generally to improvements in spray guns and is directed particularly to an improved nozzle attachment for a paint spray gun.

A principal object of the present invention is to provide a device for attachment to any ordinary type of paint spray gun, whereby the pattern of the spray projected from the gun can be controlled and by means of which a substantially fogless paint stream or spray is produced.

Another object of the invention is to provide an attachment for the nozzle end of a paint spray gun which is constructed and arranged in a novel manner whereby the air ejected with the spray is completely separated and deflected away from the paint droplets whereby the formation of mist or fog is completely avoided.

A further and important object of the present invention is to provide in an attachment for the nozzle of a spray gun, an element which functions in accordance with the law of aero-dynamics known as Bernoulli's law, to deflect the air and lighter mist particles from the paint spray whereby a perfectly clean or air free fogless spray is projected forwardly and the air is carried off through filtering elements.

Still another object of the invention is to provide a device of the character described whereby new artistic effects are made possible in sign painting and decorating and in other painting projects by reason of the fact that the device functions to produce a spray in which the droplets of paint are all of the same uniform size.

Other objects and advantages of the invention will become apparent as the description of the same proceeds and the invention will be best understood from a consideration of the following detailed description taken in connection with the accompanying drawings forming a part of the specification, with the understanding, however, that the invention is not to be limited to the exact details of construction shown and described since obvious modifications will occur to a person skilled in the art.

In the drawings:

Figure 1 is a view partly in top plan and partly in horizontal section of a device constructed in accordance with the present invention the same being shown attached to a standard type of paint spray gun.

Figure 2 is a sectional view taken substantially on the line 2—2 of Figure 1.

Figure 3 is a view in front elevation of the device, parts being broken away.

2

Figure 4 is a sectional view taken substantially on the line 4—4 of Figure 2 with parts beyond the plane of section broken away.

Figure 5 is a detailed longitudinal section taken on an enlarged scale through the modified nozzle structure.

Figure 2 shows in side elevation a common type of spray gun in connection with which the present invention is used. In this gun the hand grip 10 is designated 10 and has leading to and through it an air passage, not shown, which communicates with the coupling 11 at the bottom end of the hand grip where an air hose is connected. The numeral 12 designates the paint receptacle connection for the gun while the control trigger is designated 13 and functions to open the air line whereby to discharge air through the passage 14 in the head 15, see Figure 5, and out at the nozzle tip 16.

20 The numerals 17 and 18 designate thumb screws which respectively control the air flow to the hereinafter described Venturi-jets and paint flow, the screw 17 adjusting the position of the air valve stem 19 while the screw 18 adjusts the position of the paint control needle valve 20.

25 In accordance with the present invention the common internal atomizing nozzle is replaced by the modified nozzle here shown and generally designated 21 which nozzle is secured to the gun head by the threaded coupling ring 21a in the forward end of which the nozzle tip is secured in the manner illustrated.

Connected with the nozzle 21 to receive air therefrom are the four outwardly and rearwardly curving jet tubes 22 each of which has its outlet end or tip flattened as indicated at 23 to form a flat air jet which is directed rearwardly.

30 Secured in position upon the gun head by the locking ring 21a, as is clearly illustrated in Figure 2, is a circular plate 24 which has formed integral therewith the relatively wide collar 25. This plate has an opening 26 in its center to receive the portion of the gun head upon which the ring 21a is threaded and in order to maintain 35 the plate 24 firmly in position there is placed behind it and in encircling relation with the portion of the gun extending through the opening 26, the collar 27. Thus it will be seen that when the coupling ring 21a is threaded onto the gun head it will press the plate 24 firmly against the collar 27 to secure the plate in position.

35 The plate 24 has the two arcuate openings 28 formed therein with their major proportions above the horizontal plane of the nozzle, as shown in Figure 4 and integral with the plate 24 and lead-

ing rearwardly from each of these openings 28 is a Venturi-tube 29. These Venturi-tubes are spaced apart slightly as shown in Figure 1 to receive between them the finger hook 30 which forms a part of all spray guns and which assists in properly positioning or centering the device upon the gun head.

For the proper support of the Venturi-tubes there is provided a bracket plate 31 which is secured as a bridge across between the tubes 29 and which is provided with a slot or recess 32 to receive the portion of the gun head through which the air valve extends and mounted upon the stem of the air valve and secured firmly in position by the air valve 33, is a hook 34 which engages in the aperture 35 of the Venturi bracket and thus prevents any tendency for the Venturi-tubes to move upwardly or to prevent them from being forced upwardly in a manner which might tend to damage the plate 24 of which they form a part.

The back edge of the Venturi-plate collar 25 has formed integral therewith the relatively narrow forwardly directed flange 36 which forms a forwardly opening channel around the collar or around the perimeter of the plate 24. The purpose of this flange and channel will be hereinafter set forth.

Detachably coupled with the Venturi-plate collar 25 is the hollow circular head which is generally designated 37. This hollow head has a front wall 38 which curves upwardly and rearwardly to form the encircling side wall 39, the latter terminating in the rearwardly directed annular rim 40 which is of an inside diameter to receive the collar 25 somewhat loosely, for the purpose hereinafter described.

The front wall 38 has formed therethrough the substantially elliptical spray outlet opening 41, the long axis of which is disposed transversely of the gun in the illustrations here given but it may be disposed at any angle desired but is always maintained in the plane of the spray discharge slot 42 of the tip 16, which slot as shown in Figures 3 and 4 is relatively long and narrow.

The nozzle tip has the flattened surfaces 43 which parallel the length of the slot 42 and this portion of the tip fits into the correspondingly shaped opening 44 which is formed in the center of the back wall 45 of a rearwardly tapering air baffle or hood 46. This hood at its forward end is of a width corresponding to or slightly greater than the width of the spray discharge opening 41 and the forward end of the hood is of a height slightly greater than the height of the opening 41 as shown in Figure 2. As is also shown in this figure the forward end or edge of the hood is defined by a flange 47 which bears against the inner side of the wall 38 of the head and is secured thereto by screws 48. It will thus be seen that the hood covers at the top and sides the space lying between the nozzle and the outlet opening 41 but the lower part of the hood is open.

Secured to the lower half of the wall 39 of the head 37, adjacent to the rim thereof and by means of rivets 49 is a substantially arcuate drain baffle plate 50, the top concave edge of which has the upwardly and rearwardly extending fingers 51 which support the curved or arcuate wire 52 which constitutes a filter guard. This baffle encircles the lower half of the nozzle as is clearly shown in Figures 2 and 4.

The numeral 53 designates a cloth filter which is in the form of a bag and which is secured at its edge to a rim gasket 54 which may be formed of cardboard or any other suitable material. This

bag has an opening 55 therein through which the nozzle tip extends, when the filter bag is in position, as shown in Figure 2.

The filter bag is placed in position by placing the gasket 54 on the Venturi-plate collar 25, at which time the nozzle tip will be extended through the filter bag opening 55 in the manner illustrated.

In order to maintain the filter bag in the desired position within the head there is provided a filter bracket which is generally designated 56 and which comprises a split ring 57 which has attached to the upper half thereof by means of the forwardly and inwardly converging arm portions 58, the arcuate frame 59. As will be readily seen upon reference to Figure 2 the split ring 57 is located within the mouth of the bag at the inner edge of the gasket 54 and the arcuate frame 59 which follows the contour of the upper half of the split ring, is extended forwardly into the bag.

After this assembly has been made and the gasket has been placed in position on the collar 25 the rim of the head is applied to encircle the gasket as shown and this rim is split as indicated at 60, in Figure 1, and carries at the opposite sides of the split, the upstanding ears 61 which are connected by a screw 62, whereby the ends of the split may be drawn together to contract the rim around the gasket and collar.

As will be readily seen upon reference to Figure 3, when the head is placed in position the filter guard 52 will press the lower part of the filter bag rearwardly into the circular space defined by the Venturi-plate collar 25 while the upper half of the bag will be held forwardly over the hood 46 and away from the air jet nozzles 22. The numeral 63 designates a shutter for the spray discharge opening 41. As shown most clearly in Figure 3 this shutter comprises the relatively wide plate 64, the width of which is substantially equal to or slightly greater than the width of the opening 41 and the height of which plate is slightly greater than the height of the opening.

Extending laterally and curving rearwardly from the lower left hand corner of the plate 63, as viewed from the front of the device, is a hinge arm 65 which is pivotally joined by the pivot member 66 to the side wall of the head 37 adjacent to the rim of the head.

At the opposite side of the head from the pivot member and in line therewith, the wall of the head is provided with an aperture 67 through which extends a portion of an operating lever for the shutter, generally designated 68. This lever comprises a relatively long inner end or shank 69 which is attached to an arm 70 which corresponds to the hinge arm 65, and an outer spring finger member or terminal portion 71 which has the friction tip 72 which bears against the adjacent wall of the head. This contact between the tip 72 and the wall of the head is relatively firm or tight so that when the shutter is oscillated by manipulating the finger portion 71 and has been set in the desired position, the frictional contact will hold the shutter in such position.

It will be readily seen upon reference to Figures 2 and 3 particularly that the shutter can be lowered to a position where its top edge is below the bottom edge of the outlet opening 41 or it can be raised to partially close the opening or to completely close it if desired.

The numeral 73 generally designates an air deflector. This air deflector comprises a central body portion *a* which in cross section, as shown in Figure 2, is substantially ovate. This body portion, as shown in Figure 3 is relatively long

and is designed or adapted to lie across the rear part of the air baffle 46 below the opening 42 of the nozzle 16.

The body of the air deflector at the opposite ends thereof merges with the forwardly diverging arms b which are pivotally attached as at 74 to the opposite sides of the baffle 46 in close proximity to the rear or inner side of the shutter 63.

The body portion a of the air deflector is recessed at the rear top side thereof as indicated at c and the long axis of the body extends downwardly and forwardly and at the larger end of the oval there is fixed in the body the plug 75 in which is threaded an end of an adjustment screw 76. This screw extends downwardly and forwardly through the bottom part of the side wall of the head and, outside of the head 31 the screw carries the knurled head 77 by means of which it may be rotated so as to slightly elevate or lower the air deflector as may be desired.

The recess c in the rear top side of the air deflector body receives the lower part of the projecting portion of the nozzle and the part of the baffle in which the nozzle is enclosed so that the forward rounded surface of the body of the air deflector leads downwardly and forwardly from just below the outlet opening 42 of the nozzle. Accordingly it will be seen that the proximity of this surface particularly at the highest point thereof, can be increased or decreased with respect to the lower side of the nozzle outlet 42 to regulate the influence of the curved surface of the air foil upon the air stream issuing from the nozzle with the paint droplets.

The side wall of the filter enclosing head 31 is provided with the several circumferentially spaced drain openings 78. A drain tube 79 is provided for engagement at one end into one of these openings 78 as shown most clearly in Figure 2, the other openings being closed by suitable plugs 80.

In the use of the present device the reversed air flow through the twin Venturi-tubes 29 receives most of its force from the energy in the front air jet producing the paint spray. The air ejected forwardly with the spray possesses considerable momentum and in passing over the downwardly curved top surface of the air deflector it will tend to curve downwardly in accordance with the effect defined by Bernoulli's law.

The air ejected forwardly with the spray is separated by this action from the paint spray and is turned downwardly into the lower part of the head unit and passes backwardly and upwardly through the filter cloth to and through the openings 28 leading to the rearwardly directed Venturi-tubes. Thus this reversal of flow of the air stream separated from the paint stream combines with and fortifies the rearward flow induced by the air jets or Venturi-jets 22.

The space between the shutter 63 and the adjacent part of the front wall of the unit head, and the forward lower part of the air deflector is considerably narrower than the space between the under side of the air foil and the bottom part of the head wall so that as the air passes down around the air deflector a further venturi effect is obtained and this action causes some air to be pulled in through the opening 41 across the bottom edge thereof, by the low pressure created by the air deflector and the venturi effect in the space between the air deflector and the shutter. The spray and air are separated by this action

within approximately one half inch from the nozzle where the velocity is the highest.

After the air passes through the constricted space or throat between the lower part of the air deflector and the shutter 63 the space widens as previously stated and the air spreads out to the two sides of the nozzle head in its travel upwardly and rearwardly.

In addition to the filter cloth, the space around the baffle 46 and beneath the air deflector may be and preferably is filled with stranded metal such as steel wool, fiber glass or the like which catches and retains most of the fog or fine paint which may be carried down by the air, after which the air passes through the filtering cloth where the last of the paint is completely removed from the air. This removed paint drains to the bottom of the head and passes out through the tube 79 to a suitable receptacle.

The Venturi jets act as boosters to accelerate the movement of the air rearwardly through the filtering media.

By the action of this gun attachment perfectly clear air is ejected from the back of the unit while completely fogless paint spray is shot out through the mouth or opening 41. This fogless, fanned spray is so completely free of disturbing air currents that it can be cut down in cross section by the employment of the shutter 63.

The droplets are arranged in the form of a mass spectrograph and it is possible to block out any part of the mass spectrum that is not wanted leaving sprayed droplets of all the same uniform size. This feature makes new artistic effects possible in sign painting and decorating, etc.

All liquid caught inside the unit drains down, as stated, to the bottom to be carried off by the tube 79 to be caught and reused. The head may be rotated on the supporting Venturi plate collar as previously described so as to obtain a fan lying in any plane from vertical to horizontal and when such change is made the drain tube 79 will be shifted or changed to one of the other drain openings so as to always lead from the bottom part of the head.

Since the nozzle tip 16 fits, as previously stated, into a non-circular opening in the back of the baffle, the tip will rotate with respect to the nozzle portion 21 thus turning as a unit with the attachment or front assembly, this turning of the tip with the front assembly being made possible by loosening the wing screw 62 as previously stated.

As previously described the air deflector 73 is pivotally mounted on the pivot members 74 and is adjustable up and down by means of the screw or stem 76. This adjustment has the effect of increasing or decreasing the air deflection angle to get the best results with the different air pressures.

Another purpose of the shutter 63 is to prevent the lower lip of the mouth opening 41 from getting wet with paint. The shutter gets wet and the paint runs down into the inside of the unit rather than running down the outside of the head from the lower edge of the mouth 41.

I claim:

1. In a paint spray gun having a nozzle provided with a jet tip, an attachment having a hollow head having a front wall provided with an outlet opening, means for mounting said head on the nozzle with said opening in position for the forward discharge of the jet tip therethrough, rearwardly directed air outlets extending from

said head mounting means, an air deflector supported within the head in close proximity to said tip and having a rounded forwardly and downwardly curving surface positioned for the spray jet issuing from the tip to pass thereover, said deflector being spaced from the front wall of the head for the movement downwardly to the lower part of the head of a portion of the spray jet, and an outlet for draining off the said deflected portion of the spray jet from said head discharge through said rearwardly directed outlets.

2. A structure of the character set forth in claim 1, with filtering means within the head between the said space through which a portion of the spray jet passes and the said rearwardly directed outlets.

3. A structure of the character described in claim 1 with means within the head for filtering the said portion of the spray jet to effect separation of air from paint, means for draining off separated paint from the lower part of the head, and blowing means for forcing movement of the air through the rearwardly directed outlets.

4. An attachment for a paint spray gun comprising a nozzle having a rotatable spray tip, a plurality of jet nozzles carried by said nozzle to receive air therefrom and directed rearwardly, an enclosure for said nozzle and jet nozzles comprising a circular plate mounted upon the spray gun behind the first nozzle and having outlet openings through which the jet nozzles are directed, a hollow head, connecting means between the peripheries of the head and the plate to allow the turning of the head on the axis of the nozzle tip, said head having a forward wall provided with an outlet opening through which the nozzle tip discharges, a coupling means between the said front wall of the head and the nozzle tip whereby turning of the head effects the corresponding turning of the tip, a filtering element partitioning the said enclosing means between the head and the back wall plate, an air deflector disposed transversely of and in close proximity to the nozzle tip, said air deflector having a forwardly and laterally curving surface disposed in front of the tip in a position to have a jet issuing from the tip pass over such surface, there being a space between said air deflector surface and the front wall of the head for the passage of a portion of the spray jet into the lower part of the head, said jet nozzles functioning to facilitate rearward movement of a part of the said portion of the spray jet, and drainage means for the lower part of the head.

5. A structure of the character set forth in claim 4, with means mounting said air deflector for movement relative to the nozzle tip, and means for effecting the adjustment of the air deflector correspondingly for variations in the rate of discharge from said tip.

6. A structure of the character set forth in claim 4, with a pivotally mounted shutter for movement across the said outlet opening of the head, and means disposed upon the outer side of the head and connected through the head with the shutter for facilitating movement of the shutter and for maintaining the shutter in adjusted position relative to the head opening.

7. A paint spray gun structure of the character stated in claim 4 wherein the said connection between the front wall of the head and the nozzle tip comprises a hood having a top portion and depending side portions, and said air deflector being disposed in the lower part of the hood be-

tween said side portions and pivotally mounted for adjustment relative to the nozzle tip, and means extending outwardly of the head and for adjusting said deflector relatively to said nozzle.

5 8. A paint spray gun structure of the character stated in claim 4 wherein the said connection between the front wall of the head and the nozzle tip comprises a hood having a top portion and depending side portions, and said air deflector 10 being disposed in the lower part of the hood between said side portions and pivotally mounted for adjustment relative to the nozzle tip, and means mounted in the front wall of the head and connected with the air deflector for adjusting the 15 air deflector relatively to said nozzle, and a shutter pivotally mounted within the head for vertical oscillation within the hood and across the outlet opening of the head.

9. A spray gun construction of the character 20 stated in claim 4 wherein the said filtering means comprises an annular frame encircling the nozzle and contacting at its outside periphery against the inner surface of the head, a filter cloth encircling said annular frame and having a central 25 opening through which the nozzle tip projects, and a gasket of circular form secured to the edge of said cloth and held between the joining portions of the head and said back plate.

10. An attachment for a paint spray gun having a fanning valve, comprising a nozzle having a spray tip, a plurality of jet nozzles carried by said nozzle to receive air therefrom, the jet nozzles being positioned to discharge air rearwardly away from the tip, means for adjusting the air supply 30 to said jet nozzles being controlled by the gun fanning valve, and an enclosure for the first nozzle and the jet nozzles including a circular plate mounted upon the gun behind said first nozzle and having outlet openings through which 35 the jet nozzles are directed, the enclosure having a forward opening through which the spray tip is directed.

11. The combination with a spray gun having a nozzle provided with an outlet through which a 40 jet of air and substance propelled thereby is ejected, of a hollow head encircling said outlet and having a front opening in line therewith, and means for effecting separation of air from the substance after issuance of the jet from the outlet 45 comprising a body of elongated arcuate form supported within said head, said body having a rounded surface disposed adjacent to said outlet and immediately below the same to have the jet pass closely therover, the said body surface curving 50 forwardly and downwardly from the path of travel of the jet.

12. The combination as set forth in claim 11, with means extending through the front wall of 55 said head below the opening therein for adjusting the said body relative to said outlet to accord with different velocities of the jet.

13. In a paint spray gun having a nozzle and a jet tip, an attachment having a hollow head having a front wall provided with an outlet opening, means for mounting said head on the nozzle in position for discharge of said jet tip through said opening, means within the head for deflecting a part of a spray jet issuing from the tip away from said opening into a part of the head, means 60 for removing the deflected part of the spray jet by a way other than the outlet opening, and means for varying the area of the said outlet opening to reduce the dimensions of the spray pattern passing therethrough.

75 14. The combination with a spray gun having

a nozzle provided with an outlet through which a jet of air and substance propelled thereby is ejected, of a hollow head encircling said outlet and having an opening in line therewith, a relatively long air deflector of arcuate form disposed within the head below said outlet with the ends of the deflector directed forwardly in straddling relation with the lower part of the head opening, said deflector having a forwardly and downwardly curving top surface in close proximity to the lower side of the nozzle outlet, pivots coupling the ends of the deflector to the head for oscillation of the deflector on an axis extending transversely of the head, and means connected with the deflector for moving the same on said pivots to change the 15

position of said curved top surface relative to the nozzle outlet.

ALBERT DI STEFANO.
